(57) **CLAIM**

The ornamental design for a removable cover for a portable radio, as shown and described.

DESCRIPTION

FIG. 1 is a front view of one embodiment of a removable cover for a portable radio showing our new design;

FIG. 2 is a rear isometric view thereof;

FIG. 3 is a left side view thereof;

FIG. 4 is a right side view thereof;

FIG. 5 is a top view thereof;

FIG. 6 is a bottom view thereof; and,

FIG. 7 is a front isometric view thereof.

The broken lines shown in FIGS. 1, 2, 5 and 7 are included to define boundaries of what is claimed and form no part of the claimed design.
